US00D717870S

(12) **United States Design Patent**
Wamble

(10) **Patent No.:** **US D717,870 S**
(b4) **Date of Patent:** **** Nov. 18, 2014**

(54) **SIGN WITH INDIVIDUALIZED LETTERS**

(71) Applicant: **Architectural Safety Components, LLC**, Houston, TX (US)

(72) Inventor: **Mark Scott Wamble**, Houston, TX (US)

(73) Assignee: **Architectural Safety Components, LLC**, Houston, TX (US)

(**) Term: **14 Years**

(21) Appl. No.: **29/464,061**

(22) Filed: **Aug. 12, 2013**

(51) LOC (10) Cl. **20-03**

(52) U.S. Cl.

USPC **D20/12; D20/42**
